UNITED STATES PATENT OFFICE.

ROBERT L. PURNELL, OF RED LEVEL, ALABAMA.

WATER-PUMP.

1,389,458.

Specification of Letters Patent.

Patented Aug. 30, 1921.

Application filed June 18, 1920. Serial No. 389,921.

To all whom it may concern:

Be it known that I, ROBERT L. PURNELL, a citizen of the United States, residing at Red Level, in the county of Covington and 5 State of Alabama, have invented new and useful Improvements in Water-Pumps, of which the following is a specification.

This invention relates to pumps, particularly to pumps for pumping water, and has 10 for its object the provision of a pumping mechanism so constructed as to utilize the maximum degree of power possible for forcing water from a reservoir through suitable pipes into a storage tank or into a distributing system.

An important object is the provision of pumping cylinders of novel formation, each cylinder embodying a relatively stationary portion and a pair of oppositely movable 20 pistons, the action of the pistons toward and from each other within the relatively stationary portion resulting in compression whereby to expel the water therefrom in a very efficient manner.

Another object is the provision of pumping mechanism of this character including a train of links and levers operatively connected with the movable pistons in the cylinders, this train being driven from any 30 suitable source of power, which may be an engine, wind-mill, water-wheel, or the like.

With the above and other objects and advantages in view, the invention consists in the details of construction to be hereinafter 35 more fully described and claimed, and illustrated in the accompanying drawings in which—

Figure 1 is an elevation of the device, Fig. 2 is an elevation thereof taken at 40 right angles to Fig. 1,

Fig. 3 is a plan view,

Fig. 4 is a sectional view taken longitudinally of the mechanism and through one of the cylinders,

Fig. 5 is an end elevation of one of the cylinders, and—

Fig. 6 is a detail section through the base.

Referring more particularly to the drawings, the letter A designates a water reservoir and B designates a storage tank into which it is desired to pump water. In carrying out my invention I provide a suitable foundation 10 above which I mount a plurality of cylinders or chests 11 which are 55 identical in construction and which are trapezoidal in plan. Each of these chests

or cylinders includes a stationary member formed as a hollow metal shell and the smaller ends 12 of these members have connected therewith the pipes 13 leading into 60 an outlet pipe 14 discharging into the tank B. Each pipe 13 is provided with a check valve 15 to prevent retrograde flow of water. Entering the larger ends of the chests 11 are pipes 16 provided with check 65 valves 17 and communicating with a feed pipe 18 leading from the reservoir A.

Each member 11 is provided internally with a longitudinal bore 19 leading from the inlet to the exhaust pipe and with a transverse bore 20 intersecting the bore 19. Disposed within the opposite ends of the bore 20 are pistons 21 which are slidable through stuffing boxes 22 which are, of course, adjustable to prevent leakage. Secured upon and 75 extending in spaced relation to the members 11, are guides 23 which are slidably engaged by the pistons.

In order that the pistons may be driven, I provide a pair of suitably mounted shafts 80 24 which are provided with oppositely disposed crank portions 25 having connected therewith links 26 connected with bar 27 which are pivoted at 28, upon the smaller ends of the members 11 and which are pivotally connected, intermediate their ends, with the outer ends of the pistons, as shown at 29. These shafts 24 carry intermeshing gears 30 whereby they may be rotated simultaneously in opposite directions. 90

Disposed upon one shaft 24 are ratchet wheels 31 and associated with each ratchet wheel is a lever 32 pivoted upon the associated shaft 24 and carrying a spring-pressed pawl 33 engaging the associated 95 ratchet. The other ends of these levers 32 are connected with links 34 which are in turn connected with other links 35 slidably mounted through bearings 36 carried by a supporting bar 37. Two of the links 35 are 100 connected with crank portions 38 formed in a shaft 39 rotatably mounted in suitable bearings and this shaft 39 carries a gear 40 with which the third link 35 is eccentrically connected, as shown at 41. This 105 gear 40 is adapted for connection with any suitable power device whereby to supply the motive force for operating the pumping mechanism above described.

In the operation of the device it will be 110 seen that when the shaft 39 is rotated, the links 35 will be moved and the levers 32

will be angularly reciprocated upon one shaft 24 and this movement of the levers 42 will cause the pawls 33 to engage the ratchet wheels 31 and result in step by step movement thereof. As these pawls are arranged 5 120 degrees apart, it will be apparent that continuous rotation of both of the shafts 24 will result. As the shafts 24 rotate the links 26 and bars 27 will cause reciprocation of the piston members toward or from each other 10 and as these piston members move outwardly or apart, water will be sucked into the chests 11 through the pipe 17, and when the pistons move inwardly, will be subsequently discharged through the pipes 13 15 into the pipe 14 and thence into the storage tank or distributing system. Owing to the construction of the chests or cylinders and the pistons operating therein, it will be apparent 20 that there will be more than the usual compressing action as the water will be efficiently forced into the discharge ends of the chests.

While I have shown and described the 25 preferred embodiment of my invention, it is of course to be understood that I reserve the right to make such changes in the form, construction, and arrangement of parts as will not depart from the spirit of the invention or the scope of the subjoined claims.

Having thus described my invention, I 30 claim:

1. In a pumping mechanism including a plurality of cylinders and pistons operating 35 therein, operating means comprising a

lever for each piston pivoted at one end and pivotally connected with the piston intermediate its ends, a pair of superimposed shafts having a plurality of corresponding crank portions connected with the other end of the 40 respective levers, gear connections between said shafts whereby to effect simultaneous rotation thereof in opposite directions, and means for imparting step by step rotation to one of the shafts.

2. In a pumping mechanism including a plurality of cylinders and pistons operating 45 therein, operating means comprising a lever for each piston pivoted at one end and pivotally connected with the piston intermediate its ends, a pair of superimposed shafts having a plurality of corresponding crank portions connected with the other ends of the respective levers, gear connections between said shafts whereby to effect simultaneous rotation thereof in opposite directions, and means for imparting step by step 50 rotation to one of said shafts, said last named means comprising a plurality of ratchets on one of said shafts, a longitudinally movable link for each ratchet, a spring 55 pressed pawl carried by each link engaging the associated ratchet, a plurality of levers pivoted intermediate their ends and connected at one end with one of said links, and a 60 drive shaft having a plurality of crank portions connected with the other end of said last named lever.

In testimony whereof I affix my signature.
ROBERT L. PURNELL.
